(57) **CLAIM**

The ornamental design for a rear vehicle light, as shown and described.

DESCRIPTION

The file of this patent contains a least one drawing/photograph executed in color. Copies of this patent with color drawing(s) will be provided by the Office upon request and payment of the necessary fee.

FIG. 1 is a front view of a rear vehicle light of the present design;

FIG. 2 is a top view thereof;

FIG. 3 is a partial, front, left perspective view thereof; and, FIG. 4 is a partial, front, right perspective view thereof.

The broken lines depict portions of the rear vehicle light that form no part of the claimed design.
